UNITED STATES PATENT OFFICE.

FRITZ LUX, OF LUDWIGSHAFEN-ON-THE-RHINE, GERMANY.

SPARKING PLUG.

1,148,106.

Specification of Letters Patent. Patented July 27, 1915.

Application filed January 13, 1911. Serial No. 602,501.

To all whom it may concern:

Be it known that I, FRITZ LUX, a subject of the King of Bavaria, in the German Empire, and a resident of Ludwigshafen-on-the-Rhine, Kingdom of Bavaria, Germany, have invented certain new and useful Improvements Relating to Sparking Plugs, of which the following is a specification.

This invention relates to a novel method 10 of arranging spark gaps such as are used for the ignition plugs of internal combustion engines and similar purposes. In the spark gaps of ignition plugs and the like, failure of the spark is frequently caused by 15 the presence of oil between the electrodes or other reasons, whereby the resistance of the gap is considerably increased. It will be understood that the sure and regular working of the ignition plug is of special 20 importance in the case of internal combustion engines for use in aeroplanes, and airships.

For the purpose of diminishing the objections present in known forms of ignition 25 plugs and for obtaining sure operation, the spark gap of the ignition plug is, according to the present invention, subjected to an electrical action which produces ionization of the medium in the spark gap.

30 The invention may be carried out in various ways, some typical examples of which are shown in the accompanying drawings.

In these drawings, Figure 1 is a diagrammatic view showing one method of ionizing 35 the spark gap by means of a branched wire. Fig. 2 shows a sparking plug constructed on the principle illustrated diagrammatically in Fig. 1. Fig. 3 shows a diagram of another form of carrying out the invention 40 in which a condenser is employed.

In carrying the invention into effect according to the form shown in Fig. 1 leads $c c^1$ are connected to the source of current a , and to the electrodes of the sparking plug 45 b, b^1 .

A branch wire d , leads from the wire c , to the spark gap between the electrodes. Experiments have shown that by means of this arrangement the resistance 50 of the gap is considerably reduced so that powerful sparks may be passed with surety even in cases where the resistance between the electrodes is considerably greater than in ordinary sparking plugs. In this way the ignition of the mixture in the engine is 55 much better and more thorough, and this of course leads to increased efficiency in the

engine. The branch wire may lead from the immediate neighborhood of the spark gap, it may for instance be arranged in a groove in one of the electrodes. This is the 60 method employed in the construction of sparking plug shown in Fig. 2. In this form of sparking plug one of the electrodes h , is in the form of a metal rod. A metallic head i is arranged by means of a screw bolt i^1 on a metal rod h , which is supported in a porcelain tube m , which is in turn supported in a porcelain sleeve m^1 . The end of the rod h , remote from the metallic head i , projects through the bottom of the porcelain 70 sleeve m^1 , and this projecting end is provided with a thread h^1 , and a collar h^2 , so that it may be bound to the porcelain sleeve m^1 , by means of a nut h^3 . A milled nut h^4 is provided for fixing the rod h , and electrode i , to one pole of an inductor which is not illustrated. The electrode h is carried by a metallic body n , in a manner shown in the drawing. This body has at its end a thread n^1 , for connecting it to the porcelain 80 sleeve m^1 by means of the sleeve nut n^2 . A screw thread n^3 is provided for enabling the entire sparking plug to be screwed into the casing of a motor cylinder which casing provides the conduit to the other pole 85 of the conductor. The electrode h , is provided at the point where the spark passes with a sharp pointed or edged disk h^1 , so that oil may freely drop therefrom.

According to the invention a hollow i^2 90 is provided in the metal head i , and a branch is formed by a metallic needle p , which is held in the hollow i^2 , by means of a metallic cylinder i^3 . It is by means of this branch that the ionization of the spark takes place. 95

The method of operation of this device will be clear without further explanation.

The spark gap is arranged between the part h^1 , and the neighboring edge of the metal head i . 100

The ionization is produced by a silent discharge, that takes place between the electrodes p and h^1 , whereas the main spark jumps between the electrodes i and h^1 .

According to the form shown in Fig. 3, 105 a condenser e , is arranged in the branch wire.

The invention may also be applied to other devices than ignition plugs in which it is desired to diminish the resistance in a 110 spark gap.

Having now particularly described and

ascertained the nature of my said invention and in what manner the same is to be performed, I declare that what I claim is:

1. In a spark plug, a ground electrode, a second electrode having a main terminal, arranged to form a gap with said ground electrode and insulated therefrom, a branch terminal leading from the main terminal to a point adjacent the gap, the distance of the branch terminal from said ground electrode being greater than that of the main terminal, said branch terminal being of a more pointed shape than the main terminal.
2. An improved sparking plug comprising in combination a metal rod (*h*) serving as one electrode, a metallic body (*n*) carrying the said rod (*h*), a second rod (*k*)

having a metallic head *i*, which forms the other electrode and is provided with a depression *i*², a needle *p* thus arranged in said depression opposite to the said rod *h*, the distance of the needle *p* from the electrode *h* being greater than that of the head *i*, a porcelain sleeve *m*¹, supporting said rod *h*, means for attaching the rod *h* to the said porcelain sleeve *m*¹, and means for fixing the latter to the metallic body *n*.

In witness whereof I have hereunto set my hand in the presence of two witnesses.

FRITZ LUX.
